US00D425531S

United States Patent [19]**Largent et al.****Patent Number: Des. 425,531****Date of Patent: ** May 23, 2000**[54] **SCREEN**

[75] Inventors: **David W. Largent**, Cleveland;
Kenneth W. Seyffert, Houston;
Thomas C. Adams, Hockley, all of Tex.; **David L. Schulte**, Broussard, La.; **Guy L. McClung**, Spring, Tex.

[73] Assignee: **Tuboscope I/P, Inc.**, Houston, Tex.

[**] Term: **14 Years**

[21] Appl. No.: **29/102,627**

[22] Filed: **Mar. 29, 1999**

Related U.S. Application Data

[60] Division of application No. 09/183,003, Oct. 30, 1998, which is a continuation-in-part of application No. 09/090, 554, Jun. 4, 1998, which is a continuation-in-part of application No. 08/895,976, Jul. 17, 1997, which is a continuation-in-part of application No. 08/786,515, Jan. 21, 1997, and application No. 08/598,566, Feb. 12, 1996, abandoned, which is a continuation-in-part of application No. 08/220, 101, Mar. 30, 1994, Pat. No. 5,490,598, said application No. 08/786,515, is a continuation-in-part of application No. 08/598,566, application No. 08/504,495, Jul. 20, 1995, Pat. No. 5,598,930, and application No. 29/048,575, Jan. 4, 1996, Pat. No. Des. 377,656, which is a continuation of application No. 29/014,571, Oct. 25, 1993, Pat. No. Des. 366,040, which is a continuation-in-part of application No. 08/056,123, Apr. 30, 1993, Pat. No. 5,385,669, and application No. 08/105,696, Aug. 12, 1993, Pat. No. 5,392,925.
